ABSTRACT

This invention relates to a light-weight, high-speed punch of very simple construction comprising a constantly rotating eccentric shaft; a number of interponents, or drivers, journaled on the eccentric (one for each punch to be operated); and a number of punches slidably mounted in a guide bar are aligned with the interponents but normally not operatively connected thereto. The interponents and the punches are normally not in engagement with each other; the end of the interponent adjacent the punch being resiliently restrained, as by slight friction, in a disengaged position, leaving the other, or free, end of the interponent free to oscillate through a circular path with the rotation of the eccentric. Whenever a punch is required to be operated, a block is interposed in the path of travel of the free end of the interponent, whereby the other end of the interponent is forced by the rotation of the eccentric into engagement with the punch to push it through a punching operation. A nose on the interponent positively restores the interponent to an inoperative position at the end of that cycle of rotation. It is assumed that the card or tape to be punched will be fed by conventional feeding means.

HIGH SPEED PUNCH

BACKGROUND OF THE INVENTION

This application is a continuation-in-part of our pending application of the same title, S.N. 183,151, filed Sept. 23, 1971.

In the past, the usual construction of high-speed card punches has been to use an eccentrically mounted drive for a punching member and an interponent normally positioned to one side of the aligned eccentric operating member and punch but movable to an interposing position in which the operation of the eccentric member actuates the punch. The interponents are usually carried in an elaborate carriage, or basket, which likewise must follow the movement of the eccentrically mounted driver. Such constructions require carefully machined parts, elaborate mechanisms that are usually quite large as compared to the size of the card to be punched, and are very expensive to manufacture and maintain. In contrast to the elaborate mechanisms of the past, we have discovered that a high-speed punch can be manufactured which utilizes much simpler parts made primarily from ordinary stampings. Our construction requires much fewer parts and the entire elimination of the reciprocating basket and of all of its mechanisms. In view of this simplicity of this device, there is considerably smaller mass than heretofore known, hence this machine can operate at higher speeds and is simpler to maintain.

In the preferred form of our invention, the operating parts for each order of the punch are two: an eccentrically mounted driver driven by a constantly rotating shaft, and the punching member itself. The present device utilizes a two-armed eccentric, i.e., a lever that is mounted on the constantly rotating eccentric at an intermediate point thereof; and utilizes the principle that if the operating end of the eccentric (that is, the end which engages the punch) is slightly restrained at a position away from the punch (as by friction or magnetic force, or any force which would hold one arm in a position with a slight bias), that end will reciprocate linearly rather than follow a circular path greater than that of the eccentric itself. In one form of the invention the device requires, for each order of the punch, a simple small solenoid and a blocking member operated by the solenoid. A blocking member is not interposed between the punch and the eccentrically mounted operating member, but is dropped to stop the movement of the free end of the eccentric member, i.e., the end remote from the punch, for a short portion of each cycle of operation. Whenever a block is interposed between the free end of the eccentric lever and its normal path of travel, the free end becomes restrained and the operating end is kicked into an operating position over the punch itself. These two operating movements of the eccentric are compared in FIGS. 2 to 5 and 6 to 9, respectively.

The construction of our device utilizes fewer parts, more roughly made parts, and has much less mass; and consequently can operate at a higher speed than has heretofore been possible.

OBJECTS

The primary object of the present invention is to provide a simple, trouble-free, and high-speed punch for punching cards and like materials.

It is another object of the present invention to provide a card punch operating at speeds not heretofore economically sound.

Another object of the present invention is to provide a very small and simple punch which, for the most part, can be made out of simple stampings or easily purchased parts.

These and other objects of the invention will be apparent from a consideration of the detailed specification which follows, taken in conjunction with the drawings in which:

FIG. 1 is a perspective view of the card punch of the present invention.

FIGS. 2 to 5, inclusive, are side views of the two operating members of the present invention, i.e., the eccentrically mounted lever and the punch, taken in the 0°, 90°, 180°, and 270° positions, respectively, during an inoperative, or non-punching, cycle, and shows the normal path of travel of the free end of the eccentrically mounted lever, the view being taken along the plane indicated by the line 2—2 of FIG. 11.

FIGS. 6 to 9, inclusive, are similar to FIGS. 2 to 5, inclusive, but differ therefrom in that a solenoid operated block is interposed in the path of travel of the free end of the eccentric lever, thereby kicking the operating end into engagement with the card punch and again show the parts in the 0°, 90°, 180° and 270° positions, respectively.

FIG. 10 is an enlarged plan view of two orders of the lower end of the eccentrically mounted driver, such as taken along the plane indicated by the line 10—10 of FIG. 12, and which illustrates one method of holding the driving member in the desired inoperative position.

FIG. 11 is a plan view of the punch of the present invention, with parts broken away in order to better present the arrangement of the operative parts of this invention.

FIG. 12 is a front view of a portion of the mechanism shown in FIG. 11.

FIG. 13 is a partial plan view of another embodiment of the invention utilizing the same eccentrically mounted driver and punch, but utilizing electric magnets to prevent movement of the free ends of the eccentric levers during punching strokes.

FIG. 14 is a side view of one order of the device shown in FIG. 13.

FIG. 15 is a side view of a second embodiment of the eccentric mounting of the driver of the present invention; and

FIG. 16 is a plan view of the mechanism shown in FIG. 15.

This invention relates to a light-weight, high-speed card punch. While it normally will operate at speeds exceeding those customary in this art, the machine is light enough to be readily portable, as is shown in FIG. 1. A card punch 20 is normally enclosed in a cover 21, the sides of which are provided with a feed slot 22 for the passage of punch cards 23. Operation of the device is controlled by a suitable switch 24, as these devices are normally operated by an electric motor which runs constantly while the punch is to be operated. A power cord 25 supplies power to operate the device. Since the high-speed punches are operated by other equipment normally operating through timed and discrete pulses, the device of the present invention is provided with a

pulse synchronizer, to be later described, and the pulses are fed into the device through a cable 26.

It is believed that the operation of the present device can best be understood by describing the action of a single punch and driver, as is shown in FIGS. 2 to 9, inclusive. However, for the moment it should be noted that the punching device is mounted in side frames 30 and 31, FIGS. 11 and 12, which are interconnected by a base member 32. Suitably journaled in bearings in the side frames 30 and 31 is a drive shaft 33 which is machined to provide an eccentric section 34 between the two side frames. This shaft rotates constantly at high speed throughout the period when the punch is to be operated. An upper plate 35 carries the several individual punch controllers, such as solenoids, in the device shown in FIGS. 11 and 12, or the electromagnets shown in FIGS. 13 and 14. The base plate 32 is provided with an aligned column of apertures 36 under the eccentric shaft 34, these apertures being arranged in a single line, or column, across the device in order to punch holes in the punch card in the respective columns thereof. The punches 45 and the cooperating apertures 36 are so designed that the punch member 45 will slide easily in the aperture 36 but will be held against vibration and wobble. A somewhat simpler and less expensive construction shown particularly in FIGS. 2 to 9 is to make the slots 36 relatively large to enable easy assembly of each punch 45 and its associated driver 50, and to properly guide the punch by a guide plate 40 held across the slots 36 of the base plate.

The punch members 45 of the present invention have a lower, or punching, end of a size similar to those now normally used. As shown in FIG. 12, the lower section is preferably rectangular in shape with a slight cutting point, as shown. The other end of the punch is slightly enlarged to include an aperture 46 which is adapted to enclose a nose 54 on the interponent 50, to be described in the next paragraph. It can be noted at this point, however, that the aperture 46 in the punch member 45 is of a length sufficient to permit reciprocation of the nose 54 of the associated interponent 50 throughout its path of operation without in any way moving the punch member, except that when the punch has been operated to punch a hole in the card 23, the nose 54 engages the upper end of the aperture 46 and raises the punch to an inoperative position at the end of a cycle. It should be noted, however, that so long as there is no pulse to operate the punch in a particular columnar position, the interponent will reciprocate idly within the aperture, or slot, 46 in the punch member.

FIGS. 2 to 5, inclusive, illustrate four angular positions of the eccentrically mounted interponent of the device during an inoperative, or non-punching stroke. A punch card 23 is fed through a feed slot formed by a pair of plates 37 and 38 affixed to the lower face of the base plate 32 and separated by a spacing sufficient to permit the passage of a punch card 23 while holding it firmly against unnecessary motion. As indicated above, we prefer that the lower ends of the punches are rather firmly confined within apertures provided in a guide plate 40 rigidly mounted in the lower face of the base 32 and within the interponent apertures 36. Both of the plates 37 and 38 have an aperture 43 or 44, respectively, that registers with the punch ways in block 40 so that the punch member 45 will extend through

both plates as well as the card during a punching stroke.

It can be noted that the card can be fed by any customary means, such as card feed wheels 39 penetrating apertures of the lower plate 38 and driving the card forward through the punch. Since feed mechanisms are old and are not claimed herein, it is believed unnecessary to further describe them, as any of the various feeding mechanisms can be used to pass the cards under the row of columnar punches 45.

The various eccentrically mounted interponents, or drivers, are preferably stamped from sheet stock and take the form of double ended levers which are rotatably mounted on the eccentric portion 34 of shaft 33. 15 The upper, or free, arm 51 of each eccentric driver 50 lies opposite the front face 41 of the upper plate 35 at all times, even when in the lowermost position shown in FIG. 4 and will engage the face 41 during the upward stroke of the driver (FIG. 5). This plate 35 not only 20 provides support for certain parts of the device but it also operates to cam the upper arm forwardly (as shown in FIG. 5) during the rise of the interponent from its lowermost position shown in FIG. 4 and thus disengage the interponent from the punch member 45 25 if it happens to be engaged therewith (see FIG. 9). The lower arm 52 is shaped to provide a shoulder 53 which is adapted to engage the upper edge of the punch member 45 during the downstroke of the driver 50, that is, as it passes from the position shown in FIGS. 2 and 6 30 to that shown in FIGS. 3 and 7. It is also provided with a nose 54 which lies within the aperture 46 of the punch member 45. Also, in order to reduce friction, it is preferred to provide the nose 54 with a heel 55 which rides against the end walls 42 of the slots 36.

Normally, if both arms 51 and 52 of the eccentric driver 50 were completely unrestrained, both ends would tend to rock equally as the driver was moved on the eccentric 34. However, we have found that if a slight pressure is exerted against the lower arm 52 to hold it against free movement, the upper arm 51 will rock as shown in FIGS. 2 to 5 while the lower end moves a straight line reciprocating movement with the heel 55 always engaging the left wall 42 (as viewed in these figures) of the slot 36 in the base plate 32, and thus the shoulder 53 would never overlie the punch member 45. Such slight pressure can be exerted by a comb-type spring, but in our preferred embodiment, comprises a felt pad 56 held against the upper face of the base plate 32 by any suitable means, such as a metal plate 57. The felt pad is provided with apertures barely large enough to hold, or embrace, the arm 52 of the eccentric driver 50 and when the upper plate 57 is tightly pressed against the base plate 32 by any suitable means, such as screws (not shown), the felt is pressed into rather tight engagement with the sides of the arm 52. This construction is shown particularly in FIG. 10 and is sufficient to hold the lower arm 52 of the eccentric driver against the wall 42 which forms the end of slot 36. Conversely, when the lower arm 52 is kicked into an operative, or punching, position, in which the shoulder 53 engages the punch 45, the pressure of the felt pad against the driver would retain it in that position except for the fact that as the driver moves from its lowermost position shown in FIG. 4 to the three-quarter position shown in FIG. 9 (and FIG. 5) and thence to the starting position shown in FIG. 6 (and FIG. 2), the upper arm 51, by engaging the wall 41 of

the upper plate 35, cams the driver 50 to the inoperative position shown in FIGS. 2 and 6. Thus, instead of the lower arm 52 being semi-restrained during the upward portion of the stroke, as by friction as heretofore described, the movement of the upper arm 51 to rock the driver 50 clockwise on the eccentric 34 is made by a stronger force.

Further, it is obvious that the lower arm 52 must move (counter-clockwise or to the right as shown in FIGS. 6 to 9, inclusive) whenever a greater force than that provided by friction of felt pad 56 blocks normal travel of the upper arm 51. Such a restraining force against the upper arm can be a mechanical block 60, as shown in FIGS. 6 to 9, inclusive, or an electromagnet 81 shown in FIGS. 13 and 14. If the block 60 is depressed so that it is engaged by the upper end of the arm 51 of the eccentric driver, the lower arm 52 is kicked over the upper edge of the punch member 45 and depresses it through its punching stroke, as shown in FIG. 8. In the last half of the cycle, the eccentric rises from the position shown in FIG. 8 to that shown in FIG. 6 and the toe 54 of the eccentric, through its registration with slot 46 in the punch, lifts the punch from its fully operative, or depressed, position in FIG. 8 to that shown in FIG. 6. During the rising movement of the eccentric 50, the back edge of the arm 51 engages the face 41 of the upper bar 35 (as shown in FIG. 9) and cams the lower arm 52 clockwise to an inoperative position. Until the interaction of the arm 51 with the face 41 of the bar 35, which begins in the third quadrant of operation and is completed in about 90° of movement, the friction between the shoulder 53 on the eccentric and the upper face of the punch 45, as well as the friction of the felt pad 56, holds the two members together so that a punching stroke will be completed, even though the block 60 is removed.

The block 60 can be operated through any suitable means and for purposes of exemplification, we show the block 60 as operated by an arm 61. In the embodiment shown in FIGS. 2 to 9, inclusive, the arm 61 is operated by a suitable electromagnetic coil 62 which may take any suitable form, as, for example, a solenoid. A pulse through the coil 62 of any of the punches will pull its arm 61 downwardly, thereby depressing the associated block 60 to become engaged by the upper arm 51 of the eccentric 50. Once the arm 51 has engaged the block 60, the lower arm 52 must rock to its operative position to engage the punch 45 and the block can be immediately released, as the force of friction between the shoulder 53 and the punch 45 will keep the parts in the operating condition. As shown in FIGS. 11 and 12, the arms 61 can be mounted on bars 63 and normally will be biased to an inoperative, or raised, position by some suitable spring means, not shown.

As shown particularly in FIG. 11, in order to make the mechanisms of efficient size but to keep spacing of the punches 45 to the conventional distance, it is preferred that the operating arms 61 and their respective coils 62 be staggered on opposite sides of the device, as shown in FIG. 11. By so alternately spacing the coils 62 on opposite sides of the device, an efficient size of coil 62 can be used without any sacrifice in spacing as well as avoid complex mechanical leverages to operate the block 60. Finally, it is preferred that a limit bar 64 mounted in the end plates 30, 31 be used to limit the upward movement of the arms 61 and the block 60, as shown.

It will be obvious to those skilled in the art that some means must be provided to synchronize the pulses from the pulse-generating devices with the operation of the punch so that the blocking member 60 will be operated as the eccentric 50 reaches its raised position shown in FIGS. 2 and 6 and starts its downward stroke. This can readily be accomplished by means of a pulse synchronizer 70 of known construction which can be mounted on the drive shaft 33, as shown in FIGS. 11 and 12. Since such pulse synchronizers are of known construction, it is believed unnecessary to describe one here. It is also believed unnecessary to describe the pulse generator, or the device which feeds the necessary pulses to the solenoids or electromagnets 62, since several different devices are known and any of them would be satisfactory to operate the punch of the present invention.

FIGS. 13 and 14 illustrate another, and for some installations, a preferred blocking means for the punch of the present invention. In these two figures, the restraint of the upper arm is provided by an electromagnet 80 which is energized by a suitable coil 81. We have found that the force from a small electromagnet 80 is sufficient to overcome the force of friction provided by the felt pad 56. Since the operation of the eccentric and the punch 45 are the same as previously disclosed, it is believed sufficient to point out that only a slight frictional force is required to hold the lower arm 52 of the eccentric against operative movement, and hence only a slightly stronger magnetic force need be exerted by the electromagnet 80 to hold the upper arm 51 in the operative position shown in FIG. 14 and hence kick the lower arm 52 counter-clockwise to its operative position from that shown in this figure. Clearly, when there is no pulse through a coil, and thus the electromagnet 80 is inoperative, the upper end 51 of the driver 50 will travel along the path shown in FIGS. 2 and 5. Again, it can be noted that the spacing of the punching members 50 does not need to be altered from standard practice and that while the armatures 80 of the electromagnets enclose the upper ends 51 of the eccentrics 50, the coils 81 do not need to be side-by-side. In FIGS. 13 and 14, the arrangement is shown of one coil being placed close to the eccentric drivers 50 and the next one removed therefrom, but with the armature extended to enclose the upper end of the upper arm 51 of the eccentric.

A second form of eccentric mounting of the drivers 150 is shown in FIGS. 15 and 16. In this embodiment, the drive shaft 133 carries a pair of eccentric bearing mounts 134 rigidly mounted thereon. Each of the eccentrics 134 carries a roller bearing 134 — one race of the bearing being attached to the eccentric. The other race of the bearing 135 is mounted in an arm 136, one end of which is affixed to a resilient spring arm 137. The two spring arms 137 are firmly attached to a rear wall 120 of the device. The rotation of the shaft 133 and the eccentrics 134 causes the arms 136 to travel in a somewhat eggshaped path as the spring brackets 137 restrain one end (the left end in FIG. 15) of the arm. The free ends of the arms 136 carry a bar 149 upon which are mounted a plurality of drivers 150. The drivers 150 are much thinner than those of the previous embodiments as their hubs do not encompass an eccentric, as shown in FIG. 15. The lower arm of each driver 150 is provided with the shoulder 53, toe 54 penetrating the aperture 46 in punch member 45 and with a

heel 55 which normally engages the wall 42 of the slot 36 in base member 32. As in the former embodiment, the friction provided by a felt pad 56 clamped to the base plate by a cover plate 57 is sufficient to restrain the lower end of the arm 152 against the wall 42, or in the alternate operative position in which the shoulder 53 overlies the punch 45. At the end of each cycle of operation, the camming effect of the upper end of the upper arm 151 against the wall 41 of upper plate 35 cams the lower end to the inoperative position shown in FIG. 15. When the magnet is not energized, the lower end of the lever 150 is resiliently restrained, the upper arm 151 will oscillate freely until its movement is blocked by energization of its associated magnet 81 or operation of the block 60. In either event, the upper arm 151 is held with a greater force than that exerted by the friction of the felt pad 56 against the lower end of the lower arm 152. Consequently, the lower arm is kicked over the punch 45 and the punch is operated as heretofore described.

This embodiment of drive mounting, while a little more complex in some respects, has the advantage that the total weight of the eccentrics and parts moved thereby, can be slightly less than that in the embodiment shown particularly in FIGS. 2 to 14, inclusive. This embodiment does have the advantages that the shaft on which the drivers 150 pivot, does not rotate and therefore eliminates virtually all frictional drag and bearing wear at this point. Another advantage is that the shaft diameter can be made relatively small, thereby reducing the size of the drivers 150 and also the mass of the eccentric shaft shown in earlier embodiments. The weight, friction, balance, and constantly rotating portion of the device, i.e., the shaft 133 or 33, eccentrics 134 and arms 136, as compared to interponents 50, etc., become important when, as here, the device is being driven at high speed from the constantly rotating shaft 33 or 133.

In the present invention it is necessary to keep in mind that if one end of an eccentrically mounted lever is restrained slightly while the other end is free to travel, the restrained end will travel in an almost straight line, i.e., the heel 55 rides up and down the wall 42. Then if a greater restraint is placed upon the former free end, the first end must move. When this principle is applied to a high-speed card punch, it is seen that much of the apparatus of former punches can be eliminated, thereby increasing the speed of the punch, making it easier and cheaper to manufacture and operating at higher speeds than heretofore practical.

It will be obvious that many modifications can be made in the basic concept of the present invention. For example, while a felt pad provides sufficient friction to hold the lower end of the driving member in the desired position for inoperative cycling, other restrictive means could be used. Springs of various sorts could be applied to the arm. One such spring could be a comb spring with the teeth thereof bent against the side of the driver, or other types of springs could be applied in other ways. It is believed obvious that instead of the simple eccentric shown in our preferred embodiments, any cam means, such as a "square motion" cam, or one giving essentially a linear motion plus a lateral movement, can be used to provide movement of the driver. It is believed all such drive mountings would come under the term "eccentric," for some part of the drive

does have to be eccentric to the drive shaft bearings. Another suggestion has been to use a permanent magnet in the base plate 32 along the wall 42, thereby biasing the heel 55 against it. Likewise, various forms of blocks or restraints can be used to control the movement of the upper arm 152 of the driving member, although the preferred forms have been shown as a mechanical block 60 or an electromagnet operated from the pulse-generating source to restrain the upper arm during the first portion of a cycle of operation. These and other embodiments will be obvious to those skilled in the art and should be included within the scope of the present invention.

We claim:

1. A high-speed punch comprising:
  - a. an eccentric,
  - b. means for constantly rotating said eccentric,
  - c. a punch driver journaled on said eccentric,
  - d. a punch normally not engaged by said driver,
  - e. means on one end of said driver for engaging said punch to drive said punch in one direction,
  - f. means on said end of said driver for returning said punch to an inoperative position,
  - g. means for resiliently restraining said first mentioned end of said driver in a disengaged position with respect to said punch,
  - h. preventing means for momentarily preventing a movement of the other end of said driving member, and
  - i. means for operating said preventing means in timed relationship to the operation of said eccentric.
2. The apparatus of claim 1 wherein the preventing means is a mechanical block.
3. The apparatus of claim 1 wherein the preventing means is an electromagnet.
4. The apparatus of claim 1 wherein the eccentric comprises an eccentric shaft and the respective drive members are individually mounted on said shaft.
5. The apparatus of claim 1 wherein the eccentric is journaled in a lever, one end of which is resiliently mounted in said punch and the other end of which carries the respective driving members.
6. The apparatus of claim 1 comprising also means for forcing said driver to its inoperative position during the return of the punch to an inoperative position.
7. A high-speed punch comprising:
  - a. an eccentric providing movement of a follower in both a longitudinal and a transverse direction,
  - b. means for constantly rotating said eccentric,
  - c. a follower journaled on said eccentric,
  - d. a punch,
  - e. means on one end of said follower for engaging said punch while said follower is moving in one direction,
  - f. means on said follower for returning said punch to an inoperative position,
  - g. means for resiliently restraining said first mentioned end of said follower in one position whereby the other end of said follower travels in a circular path,
  - h. preventing means for preventing circular movement of the other end of said follower, and
  - i. means for operating said preventing means in timed relationship to the operation of said eccentric.
